Primary Examiner — Eric L Goodman*Assistant Examiner* — Darcey E Heflin(74) *Attorney, Agent, or Firm* — Karen E. Klumas(57) **CLAIM**

The ornamental design for a closure for bottle, as shown and described.

DESCRIPTION

FIG. 1 is a top, front and side perspective view of a closure for bottle in accordance with my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in FIG. 7 are directed to environment and form no part of the claimed design.

1 Claim, 4 Drawing Sheets(56)
